UNITED STATES PATENT OFFICE.

JAMES HERBERT YOUNG, OF BROOKLYN, NEW YORK, ASSIGNOR TO THOMAS YOUNG INC., OF NEW YORK, N. Y., A CORPORATION OF NEW YORK.

DESIGN FOR A TABLE COVER OR THE LIKE.

Application filed September 17, 1924. Serial No. 10,805. Term of patent 3½ years.

To all whom it may concern:

Be it known that I, JAMES HERBERT YOUNG, a citizen of the United States of America, and a resident of the city of New York, borough of Brooklyn, in the county of Kings and State of New York, have invented a new, original, and ornamental Design for Table Covers or the like, of which the following is a specification.

Reference is had to the accompanying drawing in which the figure is a plan view of a table cover or the like embodying the new design.

I claim:

The ornamental design for a table cover or the like as shown.

JAMES HERBERT YOUNG.
